UNITED STATES PATENT OFFICE.

JAMES H. AVERY, OF FRANKLIN, MASSACHUSETTS, ASSIGNOR TO PHILIP C. WENTWORTH, OF PROVIDENCE, RHODE ISLAND.

RING-TRAVELER MACHINE.

Application filed February 5, 1924. Serial No. 690,877.

To all whom it may concern:

Be it known that I, JAMES H. AVERY, a citizen of the United States, residing at Franklin, county of Norfolk, Commonwealth of Massachusetts, have invented certain new and useful Improvements in Ring-Traveller Machines, of which the following is a specification.

This invention relates to machines for forming ring travelers. For the purposes of this application I shall discuss my invention in its adaptation to the formation of a ring traveler of the "horseshoe" type, comprising a pair of terminal horns and an intermediate connecting bow. It will be understood, however, that such treatment is purely illustrative and in no way limiting, and that the vertical type of ring traveler may also be produced upon my machine. The term "ring traveler" as used herein is therefore to be construed broadly as meaning any traveler, whether for ring spinning or twisting, which travels about a ring.

The present machine, in general, is a development of the traveler forming machine disclosed in the application of Philip C. Wentworth, Ser. No. 510,919, to which reference is made as illustrative. Said machine was developed to produce the travelers shown in the Wentworth Patents Nos. 1,415,069, 1,415,070, 1,415,071, 1,415,072 and 1,415,073, all granted May 9, 1922 and No. 1,461,059, granted July 10, 1923. This traveler is of standard type, but has a peculiar temper and is provided intermediate of its ends with one or more ventilating or cooling slots or openings. Such slot or opening may be readily and accurately formed intermediate of the traveler ends in the larger sizes of travelers, but difficulty is experienced in the finer sizes on account of the limited amount of metal available for slotting. In extremely fine sizes, as where the average count ranges from 7000 to 25000 travelers per pound, this intermediate portion is actually so narrow as to be practically incapable of being accurately slotted.

In order therefore to obtain in the finer sizes of travelers the superior results which characterize the larger sizes of patented Wentworth travelers, it is necessary to diminish the metal intermediate of the traveler ends by some method other than slot-

ting. According to my present invention, I propose to effect this diminution of metal by removing equal and opposite portions of the stock intermediate of the traveler ends. This results in a traveler having terminal ends of uniform width and thickness throughout but diminishing in width from said ends towards the center or intermediate connecting portion. Preferably, the metal is removed at each longitudinal edge of 60 said intermediate connecting portion in the form of segments of a circle so as to avoid the formation of any pronounced angular edges which might interfere with the free passage of the thread or yarn thereacross. 70 This traveler forms the subject matter of the Philip C. Wentworth Patent No. 1,512,254, granted Oct. 21, 1924.

While particularly designed for producing the finer sizes of travelers, my machine 75 is capable, however, of producing all the various sizes and weights of travelers required by the trade. The production of such travelers in the complete range of sizes and weights required by the trade involves 80 several difficulties, particularly in the operation of reducing the traveler intermediate of its ends. To be commercially practical, quantity production must be possible, and in so far as may be, such production must 85 be had with existing manufacturing equipment and along the lines of accepted manufacturing practice, both on account of the heavy investment which such existing manufacturing equipment represents, and on account 90 of the proven satisfactory character and economy of such manufacturing practice.

In the commercial production of the old style, solid traveler, the accepted practice 95 has been to form the travelers on standard traveler forming machines from a continuous strip of stock of uniform width and thickness throughout its extent. The slotting machine of the Wentworth application above-referred to, followed this standard practice and utilized existing standard equipment, as does my present machine.

In my present machine, however, I remove equal opposite portions at each longitudinal edge of the strip and at definitely spaced intervals throughout the length of the strip so that these cut-away portions will be located at exactly the center of the traveler when the strip is severed and the 100 105 110

individual travelers bent to form. Inasmuch as the balance of the traveler depends upon the exact centering of these cut-away portions, and any variation either in relative extent or location of the cut-outs both as to each other and as to the traveler body will destroy such balance, it is therefore of the utmost importance that the cut-outs be accurately located. The necessity of producing the travelers in all the widely varying sizes and weights required by the trade involves, moreover, a nicety of adjustment and timing of the various operating parts of the machine.

15 While these cut-outs are capable of being stamped out, experiments have shown that the stamping operation is apt to leave a burr which will catch the thread or yarn and make for imperfect spinning or twisting. Moreover, with the extremely small sizes of travelers, stamping is not practicable on account of the narrowness of the traveler body.

In order to avoid these objections while still utilizing existing equipment and proven manufacturing methods for the production of a traveler of the type involved herein in all the varying sizes and thicknesses required by the trade, I preferably 25 reduce opposite edges of the stock between the traveler ends by simultaneously bringing thereagainst, while the stock is stationary, a pair of oppositely disposed cutters of special design. These cutters not only are 30 disposed opposite to each other but rotate at the same speed so as to prevent displacement of the stock while it is being cut. Moreover, their working faces are slightly concaved, so that the edges of the stock being milled will be rounded and hence will 35 not offer any interference to the free travel of the thread or yarn thereover in the use of the travelers. The cutters mill out equal opposite amounts at the longitudinal edges 40 of the stock at spaced intervals, whereupon the stock is severed and the individual travelers bent to form. This avoids the formation 45 of a burr, as occurs when the travelers are stamped, and inasmuch as exactly the same amount of metal is removed from each 50 side of the strip, the traveler, when formed, will be properly balanced.

As contemplated herein, the milling cutters are arranged on either side of the stock 55 feed way and are adapted to open during the feeding phase of the stock feed mechanism, so as to permit the stock to enter there-between, and to subsequently close and mill the opposite edges of the stock included 60 there-between on the non-feeding phase of the stock feed mechanism. Preferably, the milling cutters are hinged to permit them to be opened and closed in properly timed 65 relation to the feed of the stock, but obviously they may be otherwise mounted.

In order to avoid all possibility of the stock being displaced during the operation of the milling cutters, I preferably provide an intermittently effective stock clamp which operates in timed relation to the 70 stock feed mechanism to clamp the stock during the non-feeding phase thereof when the milling cutters are operating and to release the stock on the feeding phase of the stock feed mechanism when the milling 75 cutters are idle.

The construction and operation of my machine, together with a selected embodiment which well illustrates the principles involved and is in itself a form which I 80 have found satisfactory under actual working conditions, are described and shown in the accompanying specification and drawings, and the characteristic features of novelty are particularly pointed out in the appended claims.

Throughout the specification and drawings, like reference characters are correspondingly employed, and in the drawings:

Fig. 1 is a front view of a ring traveler forming machine of standard type equipped 90 in accordance with my invention.

Fig. 2 is a rear view thereof.

Fig. 3 is a detail in front elevation.

Fig. 4 is a section on the line 4—4 of 95 Fig. 3.

Figs. 4^a and 4^b are sections on the lines 4^a—4^a and 4^b—4^b, respectively, of Fig. 4, Fig. 4^b showing the milling cutters rocked 100 towards each other to mill the stock entered therebetween.

Fig. 5 is a detail view illustrating the double cam for simultaneously actuating both rocker arms for the milling cutters.

Fig. 5^a is a section on the line 5^a—5^a of 105 Fig. 4, and showing the milling cutters rocked away from each other to permit the stock to feed therebetween.

Figs. 6, 7 and 8 are detail views of the timing clutch for the stock feed mechanism.

Fig. 9 is a fragmentary view of the strip 110 of stock as oppositely notched at predetermined intervals and indicating in dotted lines the lines of severance for the formed travelers.

Fig. 10 is an enlarged detail view of a milling cutter at work and particularly showing the rounded edge produced on the stock by the concaved cutting face of the cutter, and

Fig. 11 is an end elevation of a formed traveler.

I have indicated generally at 1 the frame of a ring traveler forming machine of standard type. Journalized longitudinally of the frame 1 in suitable bearings is a cam shaft 2 which is provided at one end with fast and loose pulleys 3 and 4, respectively, over which a driving belt is adapted to be shifted 125 to connect and disconnect the drive. At its 130

opposite end the shaft 2 is provided with a hand wheel 5 by means of which the shaft may be independently rotated for purposes of adjustment.

- 5 The stock S is intermittently drawn in strip form from a suitable reel through an adjustable guideway 6 by a pair of superposed feed rolls 7 between which the stock is gripped. The rolls 7 are revolved at the same surface speed but in opposite directions by an intermittently operating drive mechanism actuated from a feed cam 8 fast on the shaft 2. This drive mechanism comprises a lever 9 (Fig. 2) which is fulcrumed at 10 on the frame 1 and has its shorter arm provided with a cam roll 11 operating in the cam path of the cam 8. The longer arm of the lever 9 is slotted at 12 to receive a stud 13 on the arm of a rotatable friction clutch 14 of standard type, (Figs. 6, 7 and 8).

Fast on the arbor 15 of said clutch is a feed roll drive gear 16 which meshes with a drive gear 17 journaled thereabove in the frame 1 to transmit the rotation of the clutch 14 to the feed rolls 7 which are mounted on the same stub shafts that carry the drive gears 16 and 17 (see Fig. 8). At its lower end, the lever is tensioned by a coil spring 18 which is fast thereto at one end and is anchored at its opposite end at 19 to the frame 1. The spring 18 returns the lever 9 to initial position after each actuation thereof by the cam 8, the effective throw of the lever being limited by an adjustable stop 20 mounted in a bracket 21 fixed on the frame 1.

Mounted in advance of the feed rolls 7 on either side of the stock guideway 6 is a revolving milling cutter 22 of special design. The cutters 22 revolve at the same surface speed and in the same direction but inasmuch as they come into contact with the stock from opposite sides, their cutting edges move in opposite directions so as to reduce the liability of displacing the stock S when milling, and are mounted for simultaneous movement towards and away from the stock in timed relation to the stock feed mechanism, the timing being such that the cutters are brought against and mill the stock on the non-feeding phase of the stock feed mechanism, and are moved away from the stock on the feeding phase of said mechanism whereby to permit the milled stock to be fed forwardly towards the stock severing and traveler forming instrumentalities. When moved against the stock, the revolving cutters mill from the longitudinal edges thereof equal opposite portions or notches S', Fig. 9, which lie at either side of the intermediate connecting portion B of the ring traveler T when formed (see Fig. 11).

Preferably the cutting faces of the milling cutters 22 are circumferentially concaved or grooved, as indicated at 23, Fig. 10, so as

to round off the edges of the notches S'. This avoids formation of sharp cutting edges over which the thread or yarn might catch in the use of the traveler. Preferably, also, the notches S' are disposed as segments of a circle so as to avoid the formation of sharp angular thread catching edges. Inasmuch as the notches are equal and opposite, the balance of the traveler is preserved.

The in and out movement of the milling cutters may be accomplished in any suitable manner. As here shown, the cutters 22 are mounted in cutter blocks 24 (Figs. 1 and 3) which are hinged in spaced ears 25 formed on a relatively fixed casting 26, and are adapted to be opened and closed in properly timed relation to the feed of the stock, by a pair of spring-tensioned rocker arms 27 which are fulcrumed at 28 to a fixed cross piece 29 (Fig. 4) and above their fulcrums are disposed for simultaneous actuation by a double cam 30—31 fast on the cam shaft 2.

The milling cutters are driven from the cam shaft 2 by a gear 32 splined to said shaft and meshing with a pinion 33 on a vertically disposed shaft 34 (Figs. 1, 3 and 4) journaled in the casting 26. At its lower end the shaft 34 is provided with a gear 35 meshing with a pair of pinions 36 on the upper ends of the arbors for the milling cutters 22 (Fig. 4^a). The ratio between the gears 35 and 36 is a two to one ratio, whereby the cutters are rotated at increased speed in relation to the speed of the shaft 2.

The casting 26 is slideable longitudinally of the machine to vary the spacement of the milled notches S' in the strip of stock according to the size and weight of traveler being produced. To this end, the casting 26 is formed at its lower end as a slide adapted to fit within a slideway 37 formed on the frame 1, and is adapted to be advanced and retracted by an adjusting screw 38, Figs. 1 and 2, which permits a micrometric adjustment of the milling cutters longitudinally. The drive gear 32 is splined to the shaft 2 and is provided with a split collar 39 (Figs. 1 and 2) within which is engaged a drag arm 40 fast to the casting 26. This avoids the necessity of re-adjusting the gears 32 and 33 each time that the casting 26 is longitudinally adjusted.

In addition to their capacity for longitudinal adjustment, the cutters may also be adjusted horizontally relative to the stock feed way 6. This may be accomplished by providing the rocker arms 27 below their fulcrums 28 with extensions 41 and by pinning to the pivoted cutter blocks 24 a pair of screws 42, as indicated at 42' in Fig. 4. Threaded on the screws 42 are nuts 45 which are provided with milled portions 44 by means of which the nuts may be turned, the extensions 41 transmitting the pressure of the levers 27 to said nuts.

In order to avoid all possibility of displacement of the stock during the milling operation, I provide an overhead stock clamp which operates intermittently in timed relation to the stock feed and clamps the stock during the non-feeding phase while the cutters are at work and releases it when the cutters separate whereby to permit the stock to advance. This stock clamp 16 consists of a headed plunger 46 (Fig. 1) which is journaled vertically in a suitable guideway 47 in the frame 1 and is actuated from the stock feed cam 8, said cam preferably having a cam piece 48 fastened to one face thereof, whereby the plunger and stock feed mechanism operate in timed relation to each other. The cam piece 48 forces the plunger down upon the stock during the non-feeding phase of rotation of the stock feed cam 8, and in such movement compresses a coil spring 49 which acts to return the plunger to normal raised position when the cam piece 48 passes off the plunger in the feeding phase of rotation of the cam 8, thus permitting the stock to again feed forwardly.

From the feed rolls 7, the milled strip passes along a suitable guideway, until its free end contacts a stop 50 adjustably mounted in the line of feed of the strip. Disposed in advance of the stop 50 is a horizontally reciprocating anvil 51 over which the stock is severed by the cooperation of a vertically reciprocating bending mechanism 52 and a stationary cutter 53. This severs the strip and the individual blanks are thereupon bent to form over the anvil 51 by a pair of oppositely disposed reciprocating bending dogs 54.

40 The mechanisms for reciprocating the anvil, bender 52 and bending dogs form no part of the present invention and are therefore not described herein, although illustrated generally in Figs. 1 and 2. It may be stated, however, that these several instrumentalities are all actuated from the cam shaft 2 in properly timed relation to each other and to the operation of the feed rolls and milling cutters.

50 Various modifications in the form and construction of my machine may obviously be resorted to if within the limits of the appended claims.

What I therefore claim and desire to secure by Letters Patent is:

1. In combination, an intermittent stock feed mechanism, a pair of oppositely disposed spaced milling cutters between which the stock is adapted to feed, and means operating in timed relation to the stock feed mechanism effective to initially open said cutters during the feeding phase of the stock feed mechanism to permit the stock to feed therebetween and effective to subsequently close said cutters to permit them to mill

equal opposite portions from the longitudinal edges of the stock included therebetween during the non-feeding phase of the stock feed mechanism.

2. In combination, an intermittent stock feed mechanism, a pair of oppositely disposed spaced milling cutters between which the stock is adapted to feed, and means operating in timed relation to the stock feed mechanism effective to initially open said cutters during the feeding phase of the stock feed mechanism to permit the stock to feed therebetween and effective to subsequently close said cutters to permit them to mill equal opposite portions from the longitudinal edges of the stock included therebetween during the non-feeding phase of the stock feed mechanism, and an intermittently effective stock clamp operating in timed relation to the stock feed mechanism to clamp the stock during the non-feeding phase thereof. 70 75 80 85 90

3. In combination, an intermittent stock feed mechanism, a pair of oppositely disposed spaced milling cutters in advance of the stock feed mechanism and between which the stock is adapted to feed, means for revolving said cutters at the same speed, and means operating in timed relation to the stock feed mechanism effective to initially open said cutters during the feeding phase of the stock feed mechanism to permit the stock to feed therebetween and effective to subsequently close said cutters to permit them to mill equal opposite portions from the edges of the stock included therebetween during the non-feeding phase of the stock feed mechanism. 95 100 105 110 115 120

4. In combination, an intermittent stock feed mechanism, a pair of oppositely disposed spaced milling cutters in advance of the stock feed mechanism and between which the stock is adapted to feed, means for revolving said cutters at the same speed, and means operating in timed relation to the stock feed mechanism effective to initially open said cutters during the feeding phase of the stock feed mechanism to permit the stock to feed therebetween and effective to subsequently close said cutters to permit them to mill equal opposite portions from the edges of the stock included therebetween during the non-feeding phase of the stock feed mechanism, and an intermittently effective stock clamp operating in timed relation to the stock feed mechanism to clamp the stock during the non-feeding phase thereof. 125 130

5. In combination, an intermittent stock feed mechanism, an adjustable support, a pair of oppositely disposed spaced milling cutters hinged to said support and between which the stock is adapted to feed, and means operating in timed relation to the stock feed mechanism effective to initially

- open said cutters during the feeding phase of the stock feed mechanism to permit the stock to feed therebetween and effective to subsequently close said cutters to permit them to mill equal opposite portions from the longitudinal edges of the stock included therebetween during the non-feeding phase of the stock feed mechanism, and means for adjusting said cutter support longitudinally.
- 10 6. In combination, an intermittent stock feed mechanism, an adjustable support, a pair of oppositely disposed spaced milling cutters hinged to said support and between which the stock is adapted to feed, and means operating in timed relation to the stock feed mechanism effective to initially open said cutters during the feeding phase of the stock feed mechanism to permit the stock to feed therebetween and effective to subsequently close said cutters to permit them to mill equal opposite portions from the longitudinal edges of the stock included therebetween during the non-feeding phase of the stock feed mechanism and means for adjusting said cutter support longitudinally, and an intermittently effective stock clamp operating in timed relation to the stock feed mechanism to clamp the stock during the non-feeding phase thereof.
- 15 7. In a ring traveler machine, the combination with stock feed mechanism and stock bending and cutting mechanisms, of a stock milling mechanism operating in timed relation to said stock feed mechanism to remove equal opposite portions of the stock in the region of the traveler bow when the traveler is formed, and means whereby said stock milling mechanism may be adjusted towards and from said bending and cutting mechanisms.
- 20 8. In a ring traveler machine, the combination with stock feed mechanism and stock bending and cutting mechanisms, of a pair of hinged milling cutters operating in timed relation to said stock feed mechanism and effective to open and permit the stock to feed therebetween on the feeding phase of the stock feed mechanism and to close on the non-feeding phase of said mechanism and remove equal opposite portions of the longitudinal edges of the stock included therebetween and which cut-outs lie in the region of the traveler bow when the traveler is formed, and means whereby said stock milling mechanism may be adjusted towards and from said bending and cutting mechanisms, and means whereby said milling cutters may be adjusted laterally relative to each other.
- 25 9. In a ring traveler machine, the combination with a stock feed mechanism and stock bending and cutting mechanisms, of a stock removing mechanism effective to remove equal opposite portions of the stock in the region of the traveler bow when the traveler is formed, and means for opening said stock removing mechanism on the feeding phase of the stock feed mechanism to permit the stock to enter and for closing said stock removing mechanism on the non-feeding phase of said mechanism to permit said portions of the stock to be removed.
- 30 10. In a ring traveler machine, the combination with a stock feed mechanism and stock bending and cutting mechanisms, of a stock removing mechanism operating in advance of said stock feed mechanism and effective to remove equal opposite portions of the stock in the region of the traveler bow when the traveler is formed, and means for opening said stock removing mechanism on the feeding phase of the stock feed mechanism to permit the stock to enter and for closing said stock removing mechanism on the non-feeding phase of said mechanism to permit said portions of the stock to be removed.
- 35 11. In combination, a cam shaft, a stock feed cam and a cutter actuating cam thereon, an intermittently operating stock feed mechanism, a pair of oppositely disposed revolving spaced milling cutters between which the stock is adapted to feed, an operative connection from said feed cam to said stock feed mechanism for intermittently actuating said mechanism, means operated from said cutter-actuating cam in timed relation to said stock feed mechanism for separating said cutters during the feeding phase of the stock feed mechanism to permit the stock to feed therebetween and for subsequently closing said cutters during the non-feeding phase of the stock feed mechanism to permit them to mill the opposite edges of the stock included therebetween, and means driven from said cam shaft for simultaneously revolving said cutters, and a stock clamp intermittently effective to clamp the stock during the non-feeding phase of the stock feed mechanism and to release it during the feeding phase of such mechanism and actuated from said feed cam in timed relation to the stock feed.
- 40 12. In combination, a cam shaft, a stock feed cam and a cutter actuating cam thereon, an intermittently operating stock feed mechanism, a pair of oppositely disposed revolving spaced milling cutters between which the stock is adapted to feed, an operative connection from said feed cam to said stock feed mechanism for intermittently actuating said mechanism, means operated from said cutter-actuating cam in timed relation to said stock feed mechanism for separating said cutters during the feeding phase of the stock feed mechanism to permit the stock to feed therebetween and for subsequently closing said cutters during the non-feeding phase of the stock feed mechanism to permit them to mill the opposite edges of the stock included therebetween, and means

driven from said cam shaft for simultaneously revolving said cutters.

13. In combination, a cam shaft, a stock feed cam and a cutter actuating cam thereon, an intermittently operating stock feed mechanism, a cutter support longitudinally adjustable relative to said shaft, a pair of oppositely disposed revolving spaced milling cutters hinged to said support in advance of the stock feed mechanism and between which the stock is adapted to feed, an operative connection from said feed cam to said stock feed mechanism for intermittently actuating said mechanism, a pair of rocker arms connected to said cutters and simultaneously operated from said cutter-actuating cam in timed relation to said stock feed mechanism

for separating said cutters during the feeding phase of the stock feed mechanism to permit the stock to feed therebetween and 20 for subsequently closing said cutters during the non-feeding phase of the stock feed mechanism to permit them to mill the opposite edges of the stock included therebetween, and a gear train driven from said cam shaft for revolving said cutters at the same surface speed.

In testimony whereof I affix my signature in presence of two witnesses.

JAMES H. AVERY.
